UNITED STATES PATENT OFFICE.

JUAN OLAGUIBEL, OF MEXICO, MEXICO.

DESIGN FOR A STATUETTE.

58,396.

Specification for Design.

Patented July 12, 1921.

Application filed May 19, 1920. Serial No. 382,603. Term of patent 7 years.

To all whom it may concern:

Be it known that I, JUAN OLAGUIBEL, a citizen of the Republic of Mexico, residing at Mexico city, Mexico, have invented a new, original, and ornamental Design for a Statuette, of which the following is a specification, reference being had to the accompanying drawing, forming part hereof.

In the drawing: Figure 1 is a side elevation, and Fig. 2 is a front view of my statuette, showing my new design.

I claim:

The ornamental design for a statuette, substantially as shown.

JUAN OLAGUIBEL.
